COLOUR TELEVISION PICTURE TUBE

Pieter Martinus van Alphen, Adriaan Gerard van Doorn, and Jan Carel Francken, Eindhoven, Netherlands, assignors, by mesne assignments, to North American Philips Company, Inc., New York, N.Y., a corporation of Delaware

Application January 17, 1956, Serial No. 559,719

Claims priority, application Netherlands January 19, 1955

5 Claims. (Cl. 313—92)

A colour television picture tube is known, which comprises a screen provided with parallel, strip-shaped element luminescing in relatively different colours upon excitation by an electron beam and distributed in a certain order of succession over the screen. Such a tube produces, it is true, a colour image, but sometimes an observer gets the impression that the strip-shaped elements luminesce separately in different colours. Then he does not get the impression of a uniformly coloured luminescent image, but of a picture divided into strips of different colours. The present invention has for its object to obviate this disadvantage.

In accordance with the invention, the colour television picture tube of the aforesaid kind has, to this end, the feature that on the observer's side of the first screen the tube comprises a second screen, which diffuses the passing light from the first screen, however, substantially only in directions transverse to the direction of length of the strip-shaped elements on the first screen. It is found that this measure can obviate the aforesaid disadvantage of the known tubes.

According to one aspect of the invention the second screen is provided with ribs extending parallel to the strip-shaped elements on the first screen. According to a further aspect of the invention these ribs operate preferably as cylinder lenses.

In accordance with the invention it is advisable to choose the transverse dimension of the ribs on the second screen to be at a maximum equal to the transverse dimension of the strip-shaped elements on the first screen. Particularly satisfactory results are obtained, if the second screen is spaced apart from the first screen by a distance which exceeds twice the focal distance of the cylinder lenses and which is preferably at least equal to four times this focal distance.

The invention will be described more fully with reference to the drawing, in which:

Fig. 1 is a schematic view of the plural screen structure of the picture tube of the invention;

Fig. 2 is a cross-sectional view of a picture tube with the new screen structure.

Fig. 1 of the drawing shows a cross-section of the screen 1 comprised in a colour television picture tube: this screen is provided with parallel, strip-shaped elements, of which the drawing shows the elements 2, 3 and 4 in cross-section. These elements have the property that they, upon being struck by an electron beam the direction of which is indicated by the arrows P, luminesce in different colours. These elements are distributed in a particular order over the screen and exhibit, in reality, an extremely small transverse dimension of about 0.1 mm. This transverse dimension is designated in the drawing by a. Each of these strip-shaped elements luminesces in one of three colours. For example the element 2 luminesces red, the element 3 blue and the element 4 green. In order to distinguish between the colours the red element 2 and the red images to be described hereinafter are designated by one vertical dash, the blue element 3 and the blue images

2

by two vertical dashes and the green element 4 and the green images by three vertical dashes.

If an observer looks through the front side (not shown) of the tube, at the screen 1, i.e. the screen 20 being assumed to be omitted, he might observe the line structure of the image on the screen subdivided into the three colours. In order to obviate this disadvantage the observer's side of the screen 1, i.e. on the right-hand side of this screen viewed in the drawing, is provided with means 20 inside the tube in order to diffuse the light emanating from the screen 1, however, in a manner such that this diffusion takes place substantially only in directions transverse to the direction of length of the elements of the screen 1. These light-diffusing means consist in the embodiment shown in the drawing of a series of straight, positive cylindrical lenses, of which the drawing shows three, i.e. the lenses 5, 6 and 7. Consequently, they have a beam effect in the plane of the drawing: they operate as planoparallel glass plates in planes at right angles to the plane of the drawing through the optical axes V—V, VI—VI and VII—VII respectively.

In the embodiment shown in the drawing each of these lenses has an operative height b in the plane of the drawing, this height being equal to the transverse dimension a 25 of each of the strip-shaped elements 2, 3 and 4.

The arrangement of each of the cylinder lenses 5, 6 and 7 with the focal points F₅, F₆ and F₇ respectively, relative to the strip-shaped elements 2, 3 and 4 is chosen to be such that each of the distances of the objects V₂, V₃ and V₄ is equal to four times the associated focal distance f₅, f₆ and f₇ respectively. This results in image distances b₂, b₃ and b₄ respectively, each of which is 1 1/3 times the associated focal distance f₅, f₆ and f₇ respectively. Thus the cylinder lenses 5, 6 and 7 produce, in the plane of the drawing, reduced images 8, 9 and 10 of the parts of the section of the strip-shaped elements 2, 3 and 4 in front of the cylinder lenses. The height c of these images is, in the arrangement shown, 1/3 of the height of the strip-shaped elements 2, 3 and 4.

Each of the lenses 5, 6 and 7 produces, however, also a reduced real image of the adjacent strip-shaped elements, these images lying approximately also in a distance of 1 1/3 times the focal distance of the lenses on the right-hand side thereof. The image of the element 3 produced by the lens 5 is designated by 11, the image of the elements 2 and 4 produced by the lens 6 by 12 and 14 respectively and the image of the element 3 produced by the lens 7 by 15. The images 16 and 17 produced by the lenses 5 and 7 respectively emanate from elements of the screen 1, which are not shown in the drawing and which are adjacent over the element 2 and below the element 4 respectively.

Thus an observer does no longer see the comparatively coarse line structure with a height a of the elements 2, 3 and 4, but (in this case) a three times finer line structure, which can hardly be considered as a line structure. This improves materially the colour image reproduction.

Instead of using the positive cylinder lenses, use may be made of negative cylinder lenses; even prisms may produce the desired effect.

The effect aimed at may be improved further, if the height of the cylinder lenses is chosen not to be equal to the height a of the strip-shaped elements, but to be smaller.

The said screen may be made of glass or of a synthetic substance. Particularly in the latter case it must be considered that the material of the screen inside the tube must not give rise to phenomena which are likely to detract from the quality of the tube.

Fig. 2 shows the screens 1 and 20 in position in the cathode-ray tube, which includes the usual electron gun 22 and deflection coils 23 at the neck end of the tube. As shown, the strip-shaped luminescent elements 2, 3 and 4

are mounted on a light-transparent glass support 24, and the screen 20 comprising the cylindrical lenses 5, 6 and 7 is spaced therefrom the proper distance to obtain the finer line structure of the invention.

What is claimed is:

1. A color television picture tube comprising an electron-receiving screen comprising a plurality of parallel, elongated, strip-shaped, electron-responsive, color-producing areas with adjacent areas producing different colored light and with some areas producing the same colored light grouped in a periodic manner on said screen, electron beam producing means on one side of said screen for exciting same, and a plurality of lenticular elements disposed on the side of said screen opposite to said one side for eliminating the line-like appearance of the screen, said lenticular elements cooperating with said color-producing areas to produce, in a transverse direction to said elongated areas, a plurality of images of each elongated, color-producing area on the side of said lenticular elements remote from said screen, whereby the objectionable line-like appearance of the screen is substantially eliminated.

2. A color television picture tube comprising an electron-receiving screen comprising a plurality of parallel, elongated, strip-shaped, electron-responsive, color-producing areas with adjacent areas producing different colored light and with some areas producing the same colored light grouped in a periodic manner on said screen, electron beam producing means on one side of said screen for exciting same, and a plurality of elongated cylindrical lenticular elements extending parallel to said strip-shaped

areas and disposed on the side of said screen opposite to said one side for eliminating the line-like appearance of the screen, a lenticular element being associated with each of said color-producing areas, said lenticular elements

5 being spaced from their associated color-producing area a distance greater than its focal length and at which, in a transverse direction to said elongated areas, a plurality of images of each color-producing area are produced on the side of said lenticular elements remote from said screen, whereby the resultant imaged line structure has at least twice the fineness of that of the electron-receiving screen.

10 3. A picture tube as set forth in claim 2 wherein the width of the elongated lenticular element is not greater than the width of the strip-shaped area.

15 4. A picture tube as set forth in claim 3 wherein the spacing between the lenticular elements and the color-producing areas is at least twice the focal length of the lenticular elements.

20 5. A picture tube as set forth in claim 4 wherein the said spacing is about four times the focal length, thereby producing three spaced images of each color-producing area of the screen.
